[57] CLAIM

The ornamental design for a microscope illuminator housing, as described.

DESCRIPTION

FIG. 1 is a front elevation of a microscope illuminator housing, showing our new design;

FIG. 2 is a rear elevation thereof;

FIG. 3 is a left side elevation thereof;

FIG. 4 is a right side elevation thereof;

FIG. 5 is a top plan view thereof;

FIG. 6 is a bottom plan view thereof; and

FIG. 7 is a side elevation thereof; the broken lines are disclosed for illustrative purposes only.

*Fig. 1.**Fig. 2.**Fig. 3.**Fig. 4.**Fig. 5.**Fig. 6.**Fig. 7.*
